UNITED STATES PATENT OFFICE.

MICHAEL J. OWENS, OF TOLEDO, OHIO, ASSIGNOR TO THE TOLEDO GLASS COMPANY, OF TOLEDO, OHIO, A CORPORATION OF OHIO.

FIRE-FINISHING MACHINE.

SPECIFICATION forming part of Letters Patent No. 761,178, dated May 31, 1904.

Application filed May 13, 1902. Serial No. 107,124. (No model.)

To all whom it may concern:

Be it known that I, MICHAEL J. OWENS, a citizen of the United States, residing at Toledo, in the county of Lucas and State of Ohio, have 5 invented certain new and useful Improvements in Fire-Finishing Machines, of which the following is a specification, reference being had therein to the accompanying drawings.

The invention consists in the construction 10 of a machine for fire-finishing glassware and in the combination therewith of a polishing device, all as more fully hereinafter described, shown, and specifically pointed out in the claims.

15 In the drawings, Figure 1 is a vertical central section through my improved machine, the section being through one-half of rotary frame which carries the supports or spindles on which the glass articles are carried through 20 the furnace, showing one of the spindles in elevation with the polishing mold or shaper in operative position. Fig. 2 is a plan view of the machine, the top of the furnace being removed to show the articles therein. Fig. 3 25 is a vertical cross-section through the furnace. Fig. 4 is a perspective view of one of the article supports or spindles and the connected parts, showing the spindle in position to receive the article.

30 In the specific form of apparatus herein shown I have illustrated a series of spindles carried on a rotating frame, the spindles being adapted to receive and hold tumblers or glasses and carry them through a fire-finishing furnace, rotating them during the interval at a comparatively low speed. A polishing mold or shaper is then brought into operative relation to the article on the spindle, which is then rotated at a much higher speed to there- 35 40 by shape and polish the article, which is then removed and the operation repeated.

A is a suitable base from which extends the vertical post A', upon which the operating parts turn.

45 B is a sleeve journaled on the post A, provided near its upper end with the arms C, one for each spindle.

On the lower end of the sleeve B is secured a worm-gear D, with which meshes a worm 50 D', driven from any suitable source to cause

the rotation of the sleeve and with it the operating parts of the machine carried thereby.

I will describe the construction and operation of the parts carried by one of the arms C, and it will be understood that the other arms 55 carry like parts and operate in a similar manner. It is quite obvious that my invention includes in its broader claims the use of a single one of these arms or spindles, as well as the machine in which a series of them are 60 grouped to be operated successively.

E is a spindle to which a glass article E' is adapted to be attached in any suitable manner. In this particular construction I have shown the spindle E provided with a head F, which 65 is adapted to be heated to such a temperature that the glass article placed thereon will adhere to the head and be held during the operations to which it is subjected. To describe in a short phrase this particular means of holding the article, I will refer to the spindle E and its head as a "hot spindle or rod." The spindle is journaled in a yoke F', secured to a shaft F'', which in turn is journaled in a vertical yoke G, formed on the outer end of the 70 75 arm C.

On the inner end of the spindle E is a bevel-pinion G', which meshes with a bevel gear-wheel G'', which is journaled on the shaft F'' and is driven by the bevel-pinion H on the 80 shaft H', journaled in brackets above the arm C. This shaft H' is driven at different speeds at different points in its rotation by the following mechanism:

Upon the shaft H' is a bevel gear-wheel a, 85 with which meshes a bevel-pinion b on the vertical shaft d, journaled in a bracket e on the arm C. Upon the lower portion of the shaft d are two gear-wheels c and h, loose upon the shaft and adapted to be connected therewith by the clutch i, which is actuated by a lever k, pivoted in the bracket l. This lever at its outer end has a roller engaging a cam m, secured to the standards n, which rise from the base.

o is a spring acting to hold the lever always in contact with the cam.

The gear-wheel c meshes with an annular gear p on a sleeve q, journaled upon the lower portion of the sleeve B. This sleeve q is pro- 100

vided with a drive-gear g' , which is driven from any suitable source of power and by any suitable connection, such as indicated in the left end of Fig. 1. The gear-wheel h meshes 5 with an annular gear r , secured to a sleeve r' , which is journaled on the sleeve g and is driven through an annular bevel-gear s , likewise connected with a drive mechanism in any suitable manner. These parts are so ar- 10 ranged that when, through the medium of the cam m , the gear-wheel c is clutched to the shaft d the shaft H' and the hot spindle E will be driven at a comparatively slow speed—say thirty revolutions a minute—but when 15 through the action of the cam m the gear-wheel h is coupled to the shaft d then the hot spindle will be driven at a high speed—say three hundred revolutions a minute. There is sufficient space between the gear-wheels c 20 and h so that the clutch i may be arrested intermediate the two, in which position the rotation of the hot spindle will cease. It is evident that the cam m may be arranged (without further illustration) so as to effect 25 these movements at the desired time in the travel of the arm C .

It is desirable and quite essential that in placing the tumbler or other glass article upon the spindle it shall be centered in the 30 true axis of rotation thereof, and to accomplish this I use the following devices: The yoke F' , carrying the spindle E , may be rocked from a horizontal to a vertical position, as shown in Figs. 1 and 4. In the operation of 35 the machine this movement is caused by the following mechanism: I is a slide working in the horizontal bearing I' , which is carried to and extends from the sleeve B above the arm C . This slide is actuated by a roller-wrist I^2 , 40 engaging in a camway J , which is secured to the top post A . The slide I is connected by the link J^1 and the arm or stud J^2 with the yoke F' , and the cam is so shaped, as shown in Fig. 2, as to raise and lower the yoke and with 45 it the spindle E . On the spindle E is slidingly secured a centering-cup K . Connected to this cup is a retracting-rod K' , which passes through a guide t on the arm J^2 and terminates in a collar u . Between the collar u and 50 the arm J^2 is a retracting-spring M . In the horizontal position of these parts the spring M is expanded and draws the cup K away from the head F of the spindle, as shown in Fig. 1. As the yoke F' and the spindle is 55 rocked through the connections described into vertical position the retracting-rod K' strikes upon a stop L , which is secured to one of the brackets on the arm C , and forces the cup outward upon the spindle, at the same time press- 60 ing the spring in until in the vertical position of the parts shown in Fig. 4 the cup will engage over the head F and form a centering means for the tumbler, which may be placed therein.

O is a glow-box supplied with fuel for combustion in any suitable manner, it being customary to use a gas-flame or Bunsen burner directed therein at any suitable point. (Not herein shown.) This glow-box is segmental in shape and open at its ends, being closed 70 upon the back and top and bottom, and is provided with a slot v on its inner face to permit the travel of the hot spindle E therethrough, as shown in Fig. 3. During the time that the article is passing through the glow-box 75 the spindle is in its horizontal position and is driven by the slow-speed drive-gear already described. I consider it by far the best arrangement to have the article passed through the glow-box in a horizontal position, 80 because as the glass becomes heated and soft if it is in a vertical position it tends to straighten or elongate by the action of gravity upon the softened glass. In the horizontal position if the tumbler is properly centered upon the hot spindle gravity will act alike upon all sides and the glass will not become distorted even if it should get quite soft 85 in the glow-box. During this travel through the glow-box the edges of the glass are properly fire-finished, and, as will be observed, the entire article is subjected to the heat of the glow-box both inside and out, and the surface as well as the edges is properly fire-finished. In order to perfectly shape the article, which may be more or less misshaped during the travel through the glow-box, I use the following mechanism: P is a former which in this case is shown of a shape corresponding to substantially one-half of the tumbler. This former is carried at the outer end of the lever P' , journaled on the brackets P^2 90 on the under side of the arm C and carrying at its inner end a roller w , engaging a camway Q , secured upon the posts n , as plainly shown in 95 Figs. 1 and 4. The cam Q is so shaped that at the time the hot spindle with the tumbler thereon emerges from the furnace the former will be moved up into contact with the under surface of the tumbler, as shown in Fig. 1. 100 At the time that the former comes into contact with the article the clutch i is disengaged from the low-speed drive-gear and engaged with the high-speed drive-gear, and the article is then rotated at, say, three hundred 105 revolutions per minute in contact with the former P , which will give it the perfect finished shape. After traveling a short distance and rotating at this speed the former is withdrawn by the proper shaping of the cam Q 110 from the article, the clutch i is shifted into its intermediate position, (shown in Fig. 1,) and the article may be knocked off of the hot spindle. This cycle of operations will be performed with each of the hot spindles during 115 the complete rotation of each arm C of the machine. 120

While I have shown a hot spindle as the

means for holding the article during the operations performed upon it, I understand that in the broader features of my invention any other suitable means of support may be employed for the article.

While I have shown a specific form of shaper and a specific form of actuating device therefor, it is understood that in the broader features of my invention I believe I am not limited to that specific form of device, but that any shaper which would come within the language of the claims and perform the functions described is within the scope of my invention.

15 What I claim as my invention is—

1. In combination with a carrier rotatable in a horizontal direction, means thereon for supporting a glass article with its longitudinal axis in a horizontal plane during the rotation of the carrier, a shaper, and means for bringing the article and shaper into operative relation.

2. In combination with a carrier rotatable in a horizontal direction, means thereon for supporting a glass article with its longitudinal axis in a horizontal plane during the rotation of the carrier, a shaper, and means for automatically bringing the article and shaper into operative relation.

3. In combination with a carrier rotatable in a horizontal direction, means thereon for supporting a glass article with its longitudinal axis in a horizontal plane during the rotation of the carrier, a shaper traveling with the carrier, and means for bringing the article and shaper into operative relation.

4. In combination with a carrier rotatable in a horizontal direction, means thereon for supporting a glass article with its longitudinal axis in a horizontal plane during the rotation of the carrier, a shaper traveling with the carrier, and means for automatically bringing the article and shaper into operative relation.

45 5. In combination with a carrier rotatable in a horizontal direction, means thereon for supporting a glass article in a horizontal plane during the rotation of the carrier said means being adapted to engage the bottom face only of said article, a shaper, and means for bringing the article and shaper into operative relation.

6. In combination with a carrier rotatable in a horizontal direction, means thereon for supporting a glass article in a horizontal plane during the rotation of the carrier said means being adapted to engage the bottom face only of said article, a shaper traveling with the carrier, and means for bringing the article and shaper into operative relation.

7. In combination with a carrier rotatable in a horizontal direction, means thereon for supporting a glass article in a horizontal plane during the rotation of the carrier said means

being adapted to engage the bottom face only 65 of said article, a shaper, and means for automatically bringing the article and shaper into operative relation.

8. In combination with a carrier rotatable in a horizontal direction, means thereon for supporting a glass article in a horizontal plane during the rotation of the carrier said means being adapted to engage the bottom face only of said article, a shaper traveling with the carrier, and means for automatically bringing the 75 article and shaper into operative relation.

9. In combination with a glow-box having an approximately horizontally disposed opening in its side, a carrier rotatable in a horizontal direction, means thereon for supporting a 80 glass article adapted to travel through the opening in the glow-box, a shaper, and means for bringing the article and shaper into operative relation.

10. In combination with a glow-box having 85 an approximately horizontally disposed opening in its side, a carrier rotatable in a horizontal direction, means thereon for supporting a glass article adapted to travel through the opening in the glow-box, said means being 90 adapted to engage the bottom face only of said article, a shaper, and means for bringing the article and shaper into operative relation.

11. In combination with a glow-box having 95 an approximately horizontally disposed opening in its side, a carrier rotatable in a horizontal direction, means thereon for supporting a glass article in a horizontal plane adapted to travel through the opening in the glow-box, a shaper, and means for bringing the article 100 and shaper into operative relation.

12. In combination with a glow-box having an approximately horizontally disposed opening in its side, a carrier rotatable in a horizontal direction, means thereon for supporting a 105 glass article in a horizontal plane adapted to travel through the opening in the glow-box, said means being adapted to engage the bottom face only of said article, a shaper, and means for bringing the article and shaper into 110 operative relation.

13. In combination with a glow-box having an approximately horizontally disposed opening in its side, a carrier rotatable in a horizontal direction, means thereon for supporting a 115 glass article in a horizontal plane, a shaper, means for bringing the shaper and article into operative relation, means for rotating the supporting means at a relatively slow speed while in the glow-box, and means for rotating the 120 article or shaper at a relatively high speed while occupying said operative relation.

14. In combination with a glow-box having an approximately horizontally disposed opening in its side, a carrier rotatable in a horizontal direction, means thereon for supporting a glass article in a horizontal plane, a shaper, means for bringing the shaper and article into 125

operative relation, and means whereby said supporting means is rotated while the article is in the glow-box and also while in the shaper.

15. The combination of a spindle E, a shaft 5 upon which it is pivoted, means for rotating the spindle, and means for moving the spindle from a horizontal to a vertical position, of a sliding centering-cup K on the spindle, and means by which it is moved into the centering 10 position for the article in moving the spindle from a horizontal position and is withdrawn from said centering position upon the movement of the spindle to a horizontal position.

16. In a fire-finishing machine, the combination of an arm C, a shaft H', a spindle E, the shaft F², the yoke F' on the shaft F², said 15 yoke having a journal-bearing thereon for the spindle, a bevel-gear connection between the

spindle E and the shaft H' and means for moving the yoke and spindle from a horizontal to 20 a vertical position.

17. In a fire-finishing machine, the combination of a support for the article, means for causing that support to travel through a glow box or furnace to fire-finish the article, a shaping device applied to the article during the travel thereof and adjustable gear mechanism for rotating the article-support at different speeds. 25

In testimony whereof I affix my signature in 30 presence of two witnesses.

MICHAEL J. OWENS.
